UNITED STATES PATENT OFFICE

AUSTIN B. BELGARD, OF CHICAGO, ILLINOIS, ASSIGNOR TO CONTINENTAL FRAME CORPORATION, OF ROCHESTER, NEW YORK, A CORPORATION OF NEW YORK

DESIGN FOR A BRIDGE FOR AN OPHTHALMIC MOUNTING

Application filed September 3, 1931. Serial No. 41,005. Term of patent 7 years.

To all whom it may concern:

Be it known that I, AUSTIN B. BELGARD, a citizen of the United States of America, residing at Chicago, in the county of Cook and State of Illinois, have invented a new, original, and ornamental Design for Bridge for an Ophthalmic Mounting, of which the following is a specification, reference being had to the accompanying drawings, forming a part thereof.

In the drawings:

Fig. 1 is a front elevation of a bridge for an ophthalmic mounting, showing my new design;

Fig. 2 is a top plan view, and

Fig. 3 is a sectional view on line 3—3 of Fig. 1.

I claim:

The ornamental design for a bridge for an ophthalmic mounting, as shown.

AUSTIN B. BELGARD.
